ADJUSTABLE DIES FOR UNITING MATERIALS

Ivan A. Williams, Portland, Oreg.

Application October 9, 1953, Serial No. 385,055

10 Claims. (Cl. 78—1)

This invention relates to adjustable dies for uniting materials and particularly pertains to adjustable dies for use in uniting overlapped portions of metal sheets by forming an integral fastener therethrough.

The presently described dies are improved forms of the dies disclosed in my U. S. Letters Patent 2,254,558, issued December 2, 1941, for Fastening Element and Method of Making the Same, and in my U. S. Letters Patent 2,288,308, issued June 30, 1942, for Punch and Die.

These dies, like those disclosed in the aforesaid Letters Patent, are designed for use together with a punch in uniting overlying pieces of material. In use, the punch and die operate to form spaced incisions entirely through both thicknesses of the material. Next the sections of the material between the incisions are deformed in the direction of motion of the advancing punch until substantial portions lie beyond the plane of that surface of the material which is adjacent the die. This deformation is accompanied by bending and stretching of portions of the material at the end zones between the spaced incisions in a pattern conforming to the shape of the punch.

The central sections of the deformed portions then are pressed against the anvil of the die by the punch with the result that they are extruded laterally. In this manner there are formed laterally extending keys which span the incisions and engage the undisplaced material on each side thereof, preventing retraction of the deformed material through the opening between the incisions. As a result, the pieces of material are locked together securely.

In the foregoing procedure for forming integral fasteners, the presently described dies have one or more of several important advantages, as follows:

First, they are easily adjustable to accommodate overlapped sheets of material having a wide range of thicknesses.

Second, not only are they adjustable to accommodate sheets of varying thickness, but the required degree of adjustment may be gauged quickly and accurately.

Third, the cutting or the anvil members of the dies are readily removable. This is important in replacing a worn or broken part, or in substituting cutting or anvil members of different dimensions.

Fourth, in view of the foregoing, each die has a remarkably long service life and may be used in lieu of a plurality of dies of different sizes.

Fifth, the dies release the work readily after each fastener-forming operation.

These novel dies are described below in connection with the drawings wherein:

Figure 1 is a view in side elevation, partly in section, of one of the presently described dies illustrated in conjunction with a punch with which it cooperates in uniting overlying sheets of material;

Figure 2 is a view in front elevation of the die of Figure 1;

Figure 3 is a plan view of the die of Figures 1 and 2;

2

Figures 4, 5 and 6 are, respectively, a side elevation, a front elevation, and a plan view, Figure 4 being partly in section, illustrating one of the presently described dies wherein the anvil is removable;

5 Figures 7, 8 and 9 are, respectively, a side elevation (partly in section), a front elevation (partly in section), and a plan view of one of the presently described dies wherein the anvil is removable and also is adjustable to selected elevations with respect to the cutting members 10 of the die; and

Figures 10, 11, 12 and 13 are, respectively, a view in side elevation (partly in section), a view in front elevation (partly in section), a plan view and a sectional view taken along the lines 13—13 of Figure 10 illustrating 15 one of the dies of the present invention wherein the anvil not only is removable, but is spring pressed for stripping the work from the die at the conclusion of the fastener-forming operation.

The die illustrated in Figures 1-3 comprises a body 20 having on one of its ends a pair of shoulders 22, 24 and a pair of recesses 26, 28 opening out to the exterior adjacent the shoulders. An anvil 30 projects outwardly from the die between the shoulders.

Although the anvil may assume various configurations 25 and have various dimensions, it is provided with a work surface 32 and a pair of opposite side faces 34 and 36. Cutters 38, 40 overlie side faces 34, 36. They are formed with outer or cutting edges 42, 44 adapted to cooperate with a punch in penetrating the work. Also, they are 30 dimensioned to project beyond work surface 32 of the anvil by a degree which determines the thickness of the work which can be accommodated by the die.

Resilient securing means are provided for securing the cutters to the body of the die and for maintaining them 35 resiliently against side faces 34, 36 of the anvil. In the illustrated form, the resilient means comprise the arcuate, outwardly bowed resilient tongues 46, 48 dimensioned to enter recesses 26, 28 respectively, and to engage frictionally the side walls thereof. Tongues 46, 48 preferably extend to the central region of the cutters, as by cutting away portions of the latter to form recesses 50, 52 defining the base portion of the tongues. The plane of the cutters thus is at an angle to the plane of the tongues at their points of connection to the cutters with 40 the result that the cutters may be placed against the side faces of the anvil with their inner edges abutting shoulders 22, 24 for absorbing the thrust of the punching operation.

The punch which cooperates with the die described 50 above in forming fasteners through overlying pieces of material 54, 56 comprises a body portion 58 and a punch portion 60. The latter is dimensioned to conform to the dimensions of the die. Adjacent its punching or work surface 62 it has on opposite edges angular forming sections 55, one of which is indicated at 64.

In operating the punch of Figures 1-3, overlying sheets of material 54, 56 are placed between the punch and the die. The punch then is advanced, whereupon, cooperating 60 with cutters 38, 40 of the die, it cuts spaced incisions entirely through both thicknesses of the material. Furthermore, the sections 66, 68 of the material between the incisions are deformed in the direction of motion of the advancing punch until they lie beyond the plane of that surface of the material which is adjacent the die. 65 This displacement is accompanied by bending and stretching portions of the material at the end zones in a pattern conforming to the shape of the forming sections 64 of the punch.

Upon each stroke of the punch, the swaged sections 70 66, 68 spread the cutters 38, 40. This is made possible by the resiliency of the cutters imparted by the resilient

tongues 46, 48 to which they are connected. The thrust of the punching operation is absorbed by shoulders 22, 24 of the die body against which the cutters abut. At the conclusion of the cutting operation the work is withdrawn from between the cutters, whereupon the latter snap back against side faces 34, 36 of the anvil ready for another stroke of the punch.

Should the cutting members become worn or broken during use, they may readily be replaced by withdrawing them from recesses 26, 28, and inserting a new pair of cutters. This also may be done where it is desired to operate upon material of a different gauge. In this case the dimensions of the cutters are selected to provide a distance between their cutting edges 42, 44 and the work surface 32 of the anvil such as to be suited for the particular gauge of the material contemplated.

The embodiment illustrated in Figures 4-6 is similar to the foregoing with the exception that a removable anvil is provided. This is useful to renew a worn or broken anvil, as well as to provide an alternate way of adapting the die for use with sheet material of varying thickness. This may be accomplished by selecting an anvil having a height as compared with the height of the cutters which is suited for the sheet material to which it is to be applied.

Accordingly the die of this embodiment comprises a body 80, one end of which is provided with a pair of spaced apart shoulders 82, 84. This end of the die body also has a pair of spaced apart recesses 86, 88 lying outside of the shoulders, and a central longitudinal bore 90. An anvil 92 is connected to the body of the die by means of a shank 94, dimensioned to be frictionally received by longitudinal bore 90 of the die body. It has a work surface 98 and a pair of opposite flat side faces 100, 102. To impart sufficient strength and stability to it, the anvil preferably is of substantial length and is contained in part in a slot 96 in the upper surface of the die body which communicates with longitudinal bore 90.

Positioned against the side faces 100, 102, respectively, of the anvil are cutting elements 104, 106. These may be constructed similarly to cutters 38, 40 of the embodiment of Figures 1-3. Their inner ends abut against shoulders 82, 84 of the die body. Their outer ends on which are the cutting surfaces 108, 110 extend a spaced distance beyond the work surface 98 of the anvil, this distance being predetermined to accommodate the particular thickness of the material which is to be the subject matter of the fastening operation.

Means are provided for maintaining cutters 104, 106 resiliently pressing against the side faces of the anvil and for releasably securing them to the die body. As in the embodiment of Figures 1-3, a preferred means of accomplishing these functions comprises attaching the cutters to resilient tongues 112, 114. The latter preferably are formed integrally with the cutters by recessing the latter at 116, 118 and forming the material defined in part by the recesses into outwardly bowed tongues in the manner indicated. This in effect accomplishes attaching the tongues to the central portion of the cutters, which in turn makes possible abutting the inner edges of the cutters against shoulders 82, 84 of the die body while contemporaneously providing an arcuate spring member which may be inserted into recesses 86, 88, frictionally engaging the side walls of the same and securing the cutters to the body of the die while maintaining them pressing yieldably against the side faces of the anvil.

The operation of the die of Figures 4-6 is similar to that of the die of Figures 1-3, described above. However, in this case not only are the cutters readily replaceable and renewable, but the anvil is also. In this manner, a new anvil may be applied as desirable or necessary to replace worn or broken parts, or to adjust the spacing between the work surface of the anvil and the cutting edges of the cutters as required for material of a particular gauge.

The die illustrated in Figures 7-9 is similar to the constructions described above, particularly that illustrated in Figures 4-6. However, in this embodiment the elevation of the anvil with respect to the cutting surfaces of the cutters is adjustable so that a single die may be employed to fasten together overlying sheets having a range of thicknesses.

Accordingly the die of Figures 7-9 has a body 130, the outer end of which has a pair of shoulders 132, 134, a pair of recesses 136, 138 lying outside the shoulders, and a central slot 140 lying between shoulders. Slot 140 communicates with a longitudinal hole 142, the inner end 144 of which is enlarged and threaded. A scale 145 is placed along a lower longitudinal edge of slot 140.

An anvil 146 is contained within the slot and projects outwardly therefrom. It has a work surface 148 and a pair of opposite side faces 150, 152. Being mounted in slot 140, it is stabilized and prevented from rotating. Being slidably received therein, the extent of its projection from the body of the die may be controlled. To this end it is affixed to a shank 154 which is slidable in hole 142 of the die body, and extends into the threaded enlarged section 144 at the inner end thereof. There it abuts a screw plug 156. Hence longitudinal adjustment of the anvil may be secured by screwing the plug in or out.

A pair of cutters 160, 162 are maintained resiliently against side faces 150, 152 respectively, of the anvil. These have cutting edges 164, 166 and their inner edges abut shoulders 132, 134. They may be maintained yieldably against the side faces of the anvil and releasably secured to the die body by means of spring tongues 168, 170 such as have been described above. Thus the cutters may be recessed at 172, 174, the material defined in part by the recess connecting to integrally formed, outwardly bowed spring tongues which are dimensioned to be received by recesses 136, 138. Tongues 168, 170 being dimensioned for frictional engagement with the sidewalls of recesses 136, 138, secure the cutters 160, 162 in operative position against the anvil.

The operation of the die of Figures 7-9 is similar to that of the die of Figures 1-3 described above. However, in this case not only are the cutters removable, but the anvil likewise is removable or adjustable to a selected working position with reference to the cutting edges of the cutters. Thus by suitable adjustment of the screw plug 156, the anvil may be raised or lowered to provide the desired working distance between anvil surface 148 and cutting edges 164, 166 of the cutters. If desired, the extent of this adjustment may be measured on scale 145, thereby facilitating adjustment of the die to accommodate work of a particular gauge.

The embodiment of Figures 10-13 is similar to the dies described hereinbefore with the exception that means are provided for resiliently urging the anvil to an extended position. This strips the work from the die after each fastener is formed, accelerating the fastening sequence.

Accordingly, in this embodiment the die comprises a body 180, the outer end of which has spaced apart shoulders 182, 184; spaced apart recesses 186, 188 lying outside the shoulders; and a central slot 190 lying between the shoulders. Slot 190 communicates with a central longitudinal hole 192 which in turn opens out into an enlarged cavity 194, the outer section of which is threaded.

An anvil 196 having a work surface 198 and a pair of opposed side faces 200, 202 is slidably mounted in slot 190 and projects outwardly therefrom. Connected to the anvil is a shank 204 which is slidably mounted in hole 192. A compression spring 206 engages the end of shank 204 and abuts a screw plug 208, threaded into the threaded section of the enlarged portion 194 of the hole, for adjusting the degree of compression of the spring.

A pair of cutters 210, 212 having cutting surfaces 214, 216 are resiliently mounted against side faces 200, 202 of the anvil. These are dimensioned to extend slightly beyond the working surface 198 of the anvil and are

releasably secured to the body of the die. Thus they are provided with integrally formed tongues 218, 220 defined in part, for example, by means of recesses 222, 224 extending to the central portion of the cutter. Tongues 218, 220 are bowed outwardly and dimensioned to be received by recesses 186, 188 in the die body, frictionally engaging the sidewalls thereof. Accordingly they provide means for yieldably mounting the cutters against the side faces of the anvil with the cutting edges 214, 216 in operative position and the inner edges abutting against shoulders 182, 184 for absorbing the thrust of the punching operation.

It will be apparent that the operation of the die of Figures 10-13 is similar to that described above for the other embodiments of this invention. However, in addition the anvil of the die of Figures 10-13 is urged outwardly continuously by spring 206. Thus after compression of the spring after each stroke of the punch, it operates to extend the anvil. This in turn strips the work from the die and facilitates presentation of a new section of the overlapped sheets for fastening together.

Thus by the present invention I have provided a die for fastening together overlying pieces of material which in addition to forming an effective integral fastener therethrough is readily adjustable to accommodate sheets of varying thickness. In addition, the adjustment may be made accurately by means of an integral gauge carried by the die. Further, the dies are provided with cutters and anvils which may be readily renewed as desirable or necessary for replacing worn or broken parts or for adjusting the distance between the working surface of the anvil and the cutting edges of the cutters to accommodate sheets of various sizes. Still further, in one of its embodiments the die operates to strip the work from itself at the conclusion of each stroke of the punch, thereby accelerating the formation of a sequence of fasteners through the material.

It is to be understood that the form of my invention, herewith shown and described, is to be taken as a preferred example of the same, and that various changes in the shape, size and arrangement of the parts may be resorted to, without departing from the spirit of my invention, or the scope of the subjoined claims.

Having thus described my invention, I claim:

1. The die comprising a body, an anvil extending outwardly from the body and having a work surface and a pair of opposed side faces; the body portion having spaced apart shoulders, a pair of recesses positioned one outside each of the shoulders, and a central slot positioned intermediate the shoulders and communicating with a longitudinal bore; a shank portion connected to the anvil, the anvil being seated in the slot and the shank portion thereof in the central bore of the die body, a pair of cutters positioned one against each of the anvil side faces and bearing at their inner ends against the shoulders of the die body, and spring means connected to the cutters and seated in the recesses for resiliently pressing the cutters against the side faces of the anvil and releasably securing them to the die body.

2. The die comprising a body, an anvil projecting outwardly from the body and having a work surface and a pair of opposed side faces, means for releasably attaching the anvil to the body, means connected to the anvil for adjusting its degree of outward projection, the body having shoulders adjacent the base of said opposed side faces of the anvil and recesses opening out outside the shoulders, a pair of cutters positioned one against each of the side faces and bearing at their inner ends against the shoulders, and spring means connected to the cutters and seated in the recesses for resiliently pressing the cutters against the side faces of the anvil and releasably securing them to the body of the die.

3. The die comprising a body, an anvil projecting outwardly from the body and having a work surface, a pair of opposed side faces, and a shank; the body having shoul-

ders adjacent the said side faces of the anvil, recesses opening out outside of the shoulders, and intermediate the shoulders a slot communicating with a central longitudinal hole; the anvil being slidably mounted in a slot with its shank portion being slidably received in said central hole, a pair of cutters positioned one against each of the said side faces of the anvil, spring means connected to the cutters and seated in the recesses for resiliently pressing the cutters against the side faces of the anvil and releasably securing them against the body of the die, and screw means threaded into the central hole and bearing against the shank portion of the anvil for adjusting the degree of outward projection of the same.

4. The die comprising a body, an anvil projecting outwardly from the body and having a work surface and a pair of opposed side faces, means connected to the anvil for adjusting the degree of outward projection of the same, gauge means operatively associated with the said body and the anvil for gauging the degree of projection of the anvil with respect to the body, a pair of cutters positioned one against each of the side faces, and spring means connected to the cutters and attached to the die body for resiliently pressing the cutters against the side faces of the anvil and releasably securing them to the body of the die.

5. The die comprising a body, an anvil extending outwardly from the body and having a work surface and a pair of opposed side faces; the body having shoulders adjacent the base of the anvil, a slot intermediate the shoulders and a central hole communicating with the slot; the anvil being slidably received in the slot, and having a shank portion slidably received in the central hole, a pair of cutters positioned one against each of said side faces of the anvil and bearing at their inner ends against said shoulders and extending beyond the plane of the work surface thereof, resilient means interconnecting the cutters and the body of the die for resiliently mounting the cutters against the said side faces of the anvil and securing them to the body of the die, and a compression spring stationed within the central hole and bearing against the anvil shank for urging the anvil a predetermined distance outwardly from the die body.

6. A die comprising a body, an anvil projecting from the outer end thereof, the anvil having an outer work surface and a pair of opposed side faces, the outer end of the body having shoulders extending laterally from the opposed side faces of the anvil, a pair of cutters positioned adjacent the opposed side faces of the anvil and bearing at their inner ends against said shoulders, and resilient securing means connected to the cutters for frictionally securing the cutters to the body and for resiliently pressing the cutters against the opposed side faces of the anvil.

7. A die comprising a body, an anvil projecting from the outer end thereof, the anvil having an outer work surface and a pair of opposed side faces, the outer end of the body having shoulders extending laterally from the opposed side faces of the anvil, a pair of cutters positioned adjacent the opposed side faces of the anvil and bearing at their inner ends against said shoulders, the body having recesses therein extending inwardly from the outer end of the body and positioned laterally outward from the cutters, and spring means connected to the cutters and frictionally seated releasably in the recesses for resiliently urging the cutters against the opposed side faces of the anvil.

8. A die comprising a body, an anvil projecting from the outer end thereof, the anvil having an outer work surface and a pair of opposed side faces, the outer end of the body having shoulders extending laterally from the opposed side faces of the anvil, a pair of cutters positioned adjacent the opposed side faces of the anvil and bearing at their inner ends against said shoulders, the body having recesses therein extending inwardly from the outer end of the body and positioned laterally outward from the cutters, and an arcuate, resilient tongue formed integrally

with each cutter and frictionally seated releasably in the recesses for resiliently urging the cutters against the opposed side faces of anvil.

9. A die comprising a body, an anvil projecting from the outer end thereof, the anvil having an outer work surface and a pair of opposed side faces, the outer end of the body having shoulders extending laterally from the opposed side faces of the anvil, a pair of cutters positioned adjacent the opposed side faces of the anvil and bearing at their inner ends against said shoulders, the body having recesses therein extending inwardly from the outer end of the body and positioned laterally outward from the cutters, and an arcuate, resilient tongue formed integrally with each cutter and frictionally seated releasably in the recesses for resiliently urging the cutters against the opposed side faces of the anvil, the tongue being bowed laterally outward from the central portion of the cutter whereby to permit the inner edge of the cutter to abut the adjacent shoulder of the body.

10. A die comprising a body, an anvil removably at-

tached to the body and projecting from the outer end thereof, the anvil having an outer work surface and a pair of opposed side faces, the outer end of the body having shoulders extending laterally from the opposed side faces of the anvil, a pair of cutters positioned adjacent the opposed side faces of the anvil and bearing at their inner ends against said shoulders, the body having recesses therein extending inwardly from the outer end of the body and positioned laterally outward from the cutters, and spring means connected to the cutters and frictionally seated releasably in the recesses for resiliently urging the cutters against the opposed side faces of the anvil.
